TRAFFIC SIGNAL

Roy M. Allen, Bloomfield, N. J.

Application December 27, 1927, Serial No. 242,755

4 Claims. (Cl. 177—337)

My invention relates to signal devices for controlling street traffic, although it might be used in connection with railways also. The object of the invention is to relieve a certain condition which now prevails in cities and small towns alike, where a densely traveled way is intersected by other ways which for considerable periods may carry no traffic at all, or very little traffic. Such conditions prevail in small towns where a highway passes through the length of the town and local traffic only uses the cross-ways. In such case if ordinary automatic signals are employed, the through traffic is stopped at regular intervals and thereby delayed needlessly, when there are no vehicles at all on the cross-ways. A similar condition may and does exist in cities, where boulevard traffic for example is denser than cross-way traffic. Various attempts have been made to remedy this by shortening the time of passage for the cross-ways, and giving the through traffic on the boulevard the right of way.

I attain my object by providing signals of a type which I may call semi-automatic, that is to say, which may be operated by hand or by an approaching vehicle on a cross-way, but in case there are several vehicles or the time of use of the cross-way exceeds a certain predetermined limit, the signals will then be changed to restore the through traffic its right of way. By this means there is no interruption of the through traffic at all unless there are actually vehicles desiring to cross on the cross-ways. Special provision of course will have to be made in such a system for left hand turns and the like.

As examples of the means by which I attain my object, the usual green, orange and red lights may be employed showing two ways up and down the boulevard and on the cross-ways. With ordinary operation the green lights will remain set for the boulevard continuously as long as there is no traffic on the cross-ways but when a vehicle approaches on a cross-way, the driver may actuate the signals at that crossing, changing to orange for the boulevard and thereafter automatically changing at the expiration of the warning period to red for the boulevard and green for the cross-ways. After the lapse of a predetermined time, say forty seconds, to allow the cross-way vehicles to cross, the lights will automatically go to orange again, and after five or ten seconds more to red for the cross-ways and to green for the boulevard, thus to remain until another manual or equivalent operation makes a change.

To actuate the signals, circuit closers placed on

the right hand side of each cross-way at the intersection with the boulevard, are sufficient. These may be either push buttons on special posts at the curb, within reach of a driver, or devices similar to the platform of a vehicle scale. The former will probably be employed where a cheap or temporary installation is desired for test purposes, or where the cross-way is too narrow for a platform in one-half thereof, and the latter where the installation is permanent. In either case the actuation of the circuit closer by hand or by the weight of the vehicle traffic on it, will close the circuit of a relay or relays which in turn control the light circuits. The first impulse which closes the cautionary light circuits, and interrupts the green light for the boulevard, also sets a timing device which will run for the predetermined time, as forty seconds, required by a vehicle in crossing and will then act to restore all signals, automatically changing both ways to orange and thereafter going green to the boulevard and red to the cross-ways.

Where numbers of vehicles are following each other upon a cross-way, either in ordinary traffic or in such cases as that of a funeral, either a special timing device must be employed or repeated operation of the circuit closer be made. My device will operate either in this manner to keep the crossing open across the traffic for one time unit or a number of units at a time, or else to open and close it after the first closure at periodic intervals only. The determination of which of these two methods of operation shall be followed is a question of policy and not of mechanics.

My invention is illustrated in the accompanying drawings, in which

Fig. 1 is a plan view of a timing mechanism adapted to automatically control signals which are initially set up by a manual or platform contrivance.

Fig. 2 is a front view of the dial or indicator of the same.

Fig. 3 is a sectional view on the line 3—3 of Fig. 1, looking in the direction of the arrows.

Fig. 4 is a diagram showing the signals at one crossing, with the control relays and timing mechanism therefor.

The general arrangement in Fig. 4 will first be referred to, before describing the apparatus. In this diagram, 1 is an operating device having a circuit closer 2 controlling circuit through wires 3—4, and supposed to be located at an intersection of a lateral way with a main way or boulevard. The contact 2 may be operated either by movable platform 1 preferably portable, over

which vehicles may be driven, or by equivalent means such as a push button or manual switch on a pole. The wires 3—4 are the starting wires for initiating a change in signals to permit traffic 5 to pass on the cross-way. Current is supplied to this circuit from a low voltage source connected across the terminals 5—6, and includes primarily winding of a relay 7 which may be called the master relay. 8 is the timing device, which when 10 started by the energization of the relay 7 runs for a predetermined length of time at a uniform speed so as to regulate and control the right of crossing initiated at the platform 1. This timing device has a contact such as 9 which is normally closed against the companion contact 10 forming a terminal of the circuit 3 of the master relay 7. The moving contact 9 is connected through the body of the timing device 8 (or in any other manner) to return wire 11 connected to the energization circuit. The timing element 8 is mounted on a shaft 12 which is rotated as stated at a uniform speed by means of a device such as a spring in which energy is stored when the contact device 2 or equivalent is operated, and its 15 rotation is regulated by the escapement mechanism 47. Timing contacts 13, 14, 15 and 16 are carried on movable arms shown at 17, 18, 19 and 20 in Fig. 2, to be presently referred to. These arms are adjustable around the shaft in order 20 to predetermine the times at which the contact 9 on the element 8 will encounter and make contact with the respective timing contacts. The contacts 13 and 15 are connected through wire 21 to relay 22 which has two windings, an energizing winding 23 and a locking winding 24. The energizing winding is connected by return wire 25 to the energizing circuit 5—6. The contact 14 is connected through wire 26 to the energizing winding 28 on relay 27 which also has a locking winding 29. The energizing winding is connected on the return side to the wire 4 and so to the terminal 5 of the energizing circuit.

The relay 22 through its locking armature 22a controls the relay 30, and the relay 27 through its locking armature 27a controls the relay 31; and these two relays 30—31 are signal relays which control the signal lamps 32, 32a, 33, 33a, 34, 34a, etc. Relay 22 has a second armature (or equivalent contacts 22b) which controls a short circuit 35, 36, 37 around the locking winding 29 of the relay 27; and conversely relay 27 has a second armature or its equivalent 27b which controls a shunt 38—39 around the locking winding 24 and its contacts of relay 22. The purpose of these shunts will be apparent from the statement of operation.

When the master relay 7 is excited, the timing device 8 is rotated by means of energy stored in a spring or equivalent device. This is indicated 60 in the diagram, where the shaft 40 is shown as carrying a ratchet wheel 48 adapted to be turned one tooth at a time by the pawl 41 on the armature lever 42 of the electromagnet 43, whose circuit 44 is closed by the contacts 45 of the master 65 relay when the latter is energized. The armature lever 42 is shown with a normally closed back contact 46 which opens when the armature is attracted.

S¹, S², S³, S⁴ are ordinary snap switches to 70 open the low voltage circuits and control the lamps 32, 32a, 33, 33a, 34, 34a under special conditions, as may be desired. In ordinary operation the switches S¹ and S⁴ are closed, and the others are open. No current is flowing in any 75 part of the circuit as it stands for open traffic

on the main way or boulevard except the current necessary to light the green light 32 for said way.

It will now be understood that my operating circuits and apparatus consist of three parts: first, the street operating device of whatever form; second, the street signal means, which may be means already installed, preferably with three signals, red, green and orange (as commonly used, omitting the orange if not wanted, which 10 can be done without any other change in the apparatus or circuit); and third, the timing means and the relays and switches, together with a source of direct current. The third division of the apparatus is enclosed in a weather-proof box, 15 which contains the timing means, the relays and switches, and if direct current is not available from the 110-volt circuit, a storage battery, with or without trickle charger. The lamps are shown in condition for normal operation with the green 20 light 32 showing on the main way or boulevard, and the red lamp 32a showing on the crossway. The 110-volt current lighting these lamps is fed through the back contacts of relays 30—31, which are standard power type relays, of a size to carry 25 and open the current required for these lamps. The relays 1, 22, 27 are all of standard telephone type, operating on a small current and only carrying sufficient energy to operate the other relays.

The timing device of Figs. 1, 2, 3 will now be described. Parallel frame plates 49—50 are connected together by posts or the like and are fitted with bearings for the power shaft 46, and the escapement shafts 51, 52, 53. The power shaft 35 carries a gear 54 meshing with a pinion 55 on shaft 51 whose gear wheel 56 meshes with pinion 57 on shaft 52 which in turn carries escape wheel 58 cooperating with the anchor escapement 59 which has a verge rod 60 and a weight 61 adjustable thereon to time the gear train 58, 56, 54, and thereby time the power shaft 46 in its rotation. This power shaft always turns in the same direction, being prevented from reverse motion by the stop pawl 62 conveniently pivoted on the upper part of the magnet frame 63. The magnet structure 43 comprises a pair of solenoids 64—65 with the upper half of their cores fixed on the yoke 66 and serving thereby to support the solenoids 64—65 on the frame 67 which 50 at its lower end carries armature 42 constituting the operating lever of the machine and having pivoted to it the operating pawl 41 which works the ratchet 48. Between the upper element of the frame and the armature 42 is a compression spring 68 adjustable as to its tension by means of screw 69 and lock nut 70. Yoke 71 carries the lower or movable halves of the two cores 72, which normally rest in the position shown in Fig. 3, retracted. The yoke 71 is 60 straddled by the armature lever 42 and prevented from falling away by the strap retainer 73, upon which for convenience is mounted the contact spring 46 before referred to and shown in Fig. 4. The spring cooperates with an adjustable contact 74 carried on an insulated support in the usual manner. A mechanical backstop for the armature 42 and its pawl 41 is provided at 76, adjustably secured to the frame.

Referring particularly to Figs. 1 and 2, the 70 contacts 13, 14, 15, 16 are shown mounted on the adjustable arms 17, 18, 19, 20 which are locked when set by the thumb nut 77. It will be understood that the angular position of these arms, and the relative distance between the contacts 13, 14, 75

etc. determines the time intervals between the lighting and extinguishing of the several lamps, 32 32a, etc. The contact 9 which in Fig. 4 is shown as a projection on the disc 8, is shown in Fig. 2 as 5 a contact arm upon the shaft 51, which is therefore the timing shaft. In order to facilitate the setting of the several arms and the angular measurement of their distances apart, I provide graduated circle 78 supported in any suitable 10 way as upon posts 79, and in order to permit the adjustment of the contacts without breaking circuit, flexible leads are soldered to the tips of the contact springs at x.

In operation, when the circuit of the solenoids 15 is closed the armature lever 42 is pulled up and the pawl 41 is lifted the distance of one tooth, the circuit of the magnet being at the same time broken at the back contact 43, and the spring 68 being placed under tension heavy enough to 20 store up sufficient energy to turn the timing device 8 with its contact 9 through one complete rotation, at a rate determined by the adjustment of the escapement or timing mechanism 47. Great latitude in adjustment is permitted by the 25 moving of the weight or ball 61 up and down on the verge rod 60, so that the cycle of rotation can be set for anything from one-half minute to at least three minutes.

The entire showing of my timing device in the 30 present application is necessarily somewhat diagrammatic, as this piece of apparatus must be designed to meet the service conditions in any particular case, e. g., if a long cycle of operation is necessary the escapement must be modified 35 and probably a stronger spring for operating it would necessitate the placing of the magnet structure 43 to the left of the escapement in Figs. 1, 3 and 4, with a longer armature lever 42, so that the distance through which the magnets 40 exert their pull would be greater.

It will of course be understood that for the 45 sake of clearness of illustration Fig. 3 shows the frame and working parts in section, with the parts shown in Fig. 2 removed therefrom. Also, in the drawings, details are eliminated so far as possible, and it will therefore be understood that I reserve the right to add any known or suitable 50 features that may be necessary or desirable in commercial operation, without departing from the invention.

In Fig. 4, I have shown in dotted lines circuit 55 connections for substituting distant control for the local control of the crossing signals. Thus, taps are taken off at 80, 81 to contacts 82 of relay 83 controlled through wire 84 from a distance, to disable the master relay 7 which is locally controlled. When the distant control relay 83 is thus got into service it is necessary to break the wire 3 at 85 which may be done by 60 any suitable and convenient form of switch. Similarly, taps 86, 87, 88, 89, 90 are taken off from the parts 12, 13 and 15, 16, 25, and 14 respectively by which all the local circuits and all the local pieces of apparatus can be controlled by impulses through wires 91 to 95 inclusive, while the relay 83 remains energized. These wires shown in dotted lines may be in a 65 cable transversing the entire length of the territory to be served, or the boulevard or principal way, and there may be taps taken off at every 70 crossing, so that all or a number of crossing signals may be operated simultaneously, and uniformly from a common point.

Disregarding the dotted lines in Fig. 4 the 75 operation of my system as thus described, is as

follows: when a car closes the contact 2 of the street device 1, current flows from the 6-volt source through the following circuit: 5, 4, 3, 7, 3, 82 (when relay 83 is deenergized and switch 85 open), 10, 9, 12, 11, 6. This energizes the 5 relay 7 which pulls up its armature and closes the contacts 45, whereupon current from the same source flows through the following circuit: 5, 4, 44, 45, 44, 43, 44, 46, 42, 44, 12, 11, 6. The electromagnet 43 becoming energized, pulls up its 10 armature lever 42, places the spring 68 under tension, and lifts pawl 41 to the next tooth of the ratchet 48, at the same time breaking its own circuit at contacts 46 and 74. The spring tension immediately produces a downward pressure 15 upon the engaged ratchet tooth, the whole gear train including shafts 40, 51, 52 commences to turn, and continues to turn for such time and at such a rate as has been predetermined by the adjustment of the weight 61 on the rod 60. The 20 turning of the shaft 51 turns the timing element 8, which is the same as the contact arm 8 in Fig. 2 and the contact 9 is thereby removed from the fixed contact 10 and after predetermined intervals of time is brought into engagement successively with contacts 13, 14, 15, 16, 10. On its leaving the contact 10, the circuit of relay 7 is broken, whereupon that relay lets go its armature and breaks the circuit of the electromagnet 25 43, which therefore cannot again pull up its armature until after the timing element 8 shall have made one complete rotation. When the contact 9 engages contact 13, it closes the following circuit: 5, 25, 23, 21, 13, 9, 12, 11, 6. This energizes electromagnet 22, which pulls up its 30 armature 22a-22b. The first of these closes the following circuit: 5, 96, 97, relay 30, 98, 22a, 24, 37, 6. Thus the relay 30, which in turn pulls up its armature, breaks the circuit of the green lamp 32 on the main way and the red lamp 32a 40 on the cross-way and through its front contact supplies 110-volt current to both the orange lamps 33-33a showing on the main way and the cross-way respectively.

As the timing device proceeds in its rotation, 45 contact 9 engages with contact 14 and closes the following circuit, 5, 99, 28, 26, 14, 9, 12, 11, 6. This energizes relay 21, which pulls up its armatures 21a and 21b the first of which closes the following circuit: 5, 100, 31, 101, 27a, 29, 102, 6. 50 The second armature closes the following circuit: 22a, 38, 27b, 39, 37. As this is a short circuit around the locking circuit 24 of relay 22, the latter relay immediately lets go its armature, which breaks the circuit of the relay 30, which 55 in turn lets go and extinguishes the orange lamps 33-33a. It is prevented from relighting the lamps 32-32a however by the simultaneous energization of the relay 31, which opens the circuit 103 leading from the 110-volt terminals 60 to the contacts of relay 30, and at the same time closes the circuit 104 of the red lamp 34 on the main way and the green 34a on the cross-way.

Through its armature 27a the relay 27 has closed its own locking circuit through winding 65 29, and this condition therefore prevails until the timing device contact 9 reaches and engages the contact 15, whereupon it closes the following circuit: 5, 25, 23, 21, 15, 9, 12, 11, 6. This again energizes relay 22 the armature 22b of 70 which closes the following shunt circuit around the locking contacts of relay 27: 27a, 35, 22b, 36, 102. The relay 27 therefore immediately lets go its armature, deenergizing relay 31, which extinguishes the red lamp 34 on the main way and 75

the green lamp 34a on the cross-way. At the same time, the armature 22a of relay 22 being attracted again closes its own locking circuit and also the circuit of the relay 30, which thereupon pulls up and lights the two orange lamps 33—33a looking down the main way and the cross-way respectively.

The timing element 8 continues the rotation until contact 9 reaches contact 16, whereupon it 10 closes the following shunt circuit: 22a, 105, 16, 9, 12, 11, 37, 24. Relay 22 being disabled by this shunt circuit lets go its armature, deenergizing relay 30, extinguishing the orange lamps and relighting the green lamp 32 on the main way and 15 the red lamp 32a on the cross-way. The timing device then continues its rotation until the contact 9 reaches the fixed contact 10, whereupon it stops by reason of the limit of travel of the armature lever 42, whose contact 46 has in the 20 meantime reengaged its anvil contact 74. Thus all the parts are restored to their normal condition after one rotation of the timing device 8.

In the event that no other car is waiting on the cross-way at either side of the main way, the 25 contact 9 stops at contact 10 and the green light 32 remains lighted indefinitely; but on the other hand if a car is standing on the platform 1 of the street device awaiting a chance to cross, when contact 9—10 is established by the contact 30 arm or timer 8, the timing device is immediately reoperated and the contact arm 8 will continue to rotate so long as traffic may demand.

This timing device provides, within limits, for making the time of a complete cycle anything 35 that may be desired, and if divided up the total time of the cycle so that each step in the operation may have any fraction determined upon; so it is evident that extreme control can be secured to meet all traffic conditions. However, 40 should it be necessary under some city traffic conditions to vary the operation for a portion of the time during certain hours of the day, this can be accomplished by the use of distant control (with 6 wires for full metallic circuit), and 45 the use of relay 83, which cuts off local operation, while impulses sent out over the several wires 91 to 95 inclusive from a central control station replace the contacts produced by the arm 8 engaging the fixed arms 13, 14, 15, 16. As 50 already stated, in this way all the signals on a street several miles long may be operated simultaneously, if desired, as is now done in many cities.

It should be noted that while I have shown 55 only two sets of lamp signals at the left hand side of Fig. 4, there may be as many or as few of these as are desired in any particular case. The green lamp 32 and the red lamp 32a may typify two pairs of signal lamps looking in opposite 60 site directions on the main way or boulevard and on the cross-way, respectively; or in the event that there are more than two ways intersecting at the particular point, there may be as many more of these lamps as are necessary to 65 block the cross ways. The main feature is that the boulevard or main way is normally open to traffic, and is held so unless traffic actually approaches from a cross-way, which initiates a change in the signals, thereafter carried through 70 its various phases and completed automatically by the timing device.

Hitherto I have discussed this invention as applied to motor traffic on highways, only. It will be noted however that I have used the word 75 "ways" instead of "roads" or "streets". This was

done in order to include other sorts of traffic than motor traffic only, viz: railroad, and even a water traffic where applicable. Railway traffic is well within the scope and purview of the invention, and in so far as the present invention 5 is applicable thereto in its entirety or any of its parts, such application is contemplated by me and is intended to be covered in the appended claims.

It is to be observed that whether used for rail traffic or road traffic, and whether the cross-way traffic consists of isolated single vehicles or of a stream of vehicles across the platform 1, the proper adjustment of the arms 17, 18, 19, 20 can be made to always provide for a definite period 10 from 14 to 16 for freedom on the cross-way, and an equally definite period from 16 to 14 for freedom on the main way. The relative lengths of these periods can be anything desired, within reasonable limits, as already described.

It is to be observed that I have described the timing device as spring actuated only. Where cost is a secondary consideration, this timing device will be constructed more substantially, especially where it is expected to carry a load such as that of a number of stations through the dotted line circuits in Fig. 4. Thus, instead of the spring motor and the ratchet actuated by the electromagnet 43, the timing device 8 and its shaft may in practice be driven by an electric motor having its circuit controlled by a pair of contacts opened and closed by a cam on the member 8, or the like. This cam may be coincident with the contact projection 9, as to its operation, to open the circuit of the motor whenever the contact 9 rests upon the contact 10, and to close it at all other times. In operation, the master relay 7 would initially close the circuit of the motor, which would start the disc or arm 8 around, whereupon the cam on the disc would 30 pass away from the motor springs and allow the same to close, and to remain closed turning the timing device steadily until one complete rotation is effected, whereupon the cam will again open the motor springs, and as the circuit of the master relay has opened in the meantime, the timing mechanism will stop. Various other arrangements for this same purpose may be devised or adapted from this or other arts without departure from my invention, and I wish it 35 understood that these are all included within the scope of the claims.

What I claim is:

1. A signaling system arranged at the intersection of a highway and a crossroad for regulating 55 traffic, said system including a highway lamp circuit and a crossroad lamp circuit for the routine control of traffic, a pair of relays for alternately opening and closing said lamp circuits, circuits for said relays, an energizing winding and a locking 60 winding on each relay, a circuit extending from each locking winding to a source of current, and adapted to be closed when the relay is energized, contacts on each relay adapted when that relay is energized to disable the locking circuit 65 of the other, and a time controlled switch associated with said relays for alternately closing and opening the energizing windings on said relays, said switch being normally idle in an initial position with both said energizing circuits open so 70 as to normally retain the highway circuit closed to permit highway traffic to cross the intersection, means actuated by a vehicle approaching the intersection on the crossroad for actuating the switch so as to alternately energize and de- 75

energize said interlocking relays to successively signal the right of way to the crossroad and highway, said means including the time controlled switch and being operative for automatically restoring the switch, the relays, and the lamp circuits to their initial positions.

2. A street crossing signaling system including a pair of signal circuits, each circuit including a go signal on one street and a stop signal on the other street, a time controlled switching means for successively and alternately reversing the open and closed positions of the circuits for predetermined periods of time, a vehicle actuated means for initiating the operation of said time controlled switching means, said vehicle actuated means including energy storing means operated by the vehicle actuation for storing sufficient energy to operate the time switch through one complete cycle, and means operated by the time switch for disconnecting the vehicle actuated means during the operation of the time switch.

3. A street crossing signaling system including a pair of signal circuits, each signal circuit containing three signals, go, caution and stop, one circuit normally showing a go signal on one street and the other circuit a stop signal on the other street, a time controlled switching means for showing a cycle of signals from go through caution to stop and then through caution to go and vice versa for the other circuit normally set at stop, a vehicle actuated means for initiating the operation of said time controlled switching means, said vehicle actuated means including energy storing means operated by the vehicle actuation for storing sufficient energy to operate the time switch through one complete cycle and means operated by the time switch for discon-

necting the vehicle actuated means during the operation of the time switch.

4. A street crossing signaling system for interfering lanes thereat, including a pair of signal circuits, one circuit including a stop signal for one lane and a go signal for an interfering lane, and the second circuit including a go signal for the said one lane, and a stop signal for said interfering lane, and control means for said signal circuits; a central traffic control including connections to said control means and also time control means, and when operative rendering said connections in one operative condition for a predetermined time to apply said control means to said signal circuits to energize one of said signal circuits, repeatedly alternated with a different operative condition to apply said control means to said signal circuits to energize the said other signal circuit for a predetermined time; a normally inactive time controlled mechanism, said mechanism, when inactive, applying said control means to said signal circuits to energize one signal circuit and deenergize the other signal circuit, and when activated, applying said control means to said signal circuits first to deenergize the said one signal circuit while energizing the said other signal circuit for a predetermined period, and thereafter returning to inactive condition, a device actuated by traffic in one of said lanes, means connected to said mechanism and operated when said device is actuated to activate said mechanism; and a switching mechanism operable when said central control is operating to disconnect the last said means from said mechanism whereby the central control connection is operative to operate said signal circuit control means.

ROY M. ALLEN.
